UNITED STATES PATENT OFFICE

169,856

RAILWAY CAR BODY

Stanley W. Kay, Chicago, Ill., assignor to Pullman-Standard Car Manufacturing Company, Chicago, Ill., a corporation of Delaware

Application June 27, 1952, Serial No. 20,376

Term of patent 14 years

(Cl. D66—1)

To all whom it may concern:

Be it known that I, Stanley W. Kay, a citizen of the United States of America and resident of Chicago, county of Cook and State of Illinois, have invented a new, original, and ornamental Design for a Railway Car Body, of which the following is a specification, reference being had to the accompanying drawings, forming part thereof.

In the drawings—

Fig. 1 is a perspective view of a railway car in which my new design is incorporated, having portions broken away better to reveal the disposition of the cocktail lounge within the vehicle and showing a supporting truck in dotted lines;

Fig. 2 is a horizontal mid-sectional view taken through the vehicle showing the cocktail lounge in plan;

Fig. 3 is a vertical longitudinal sectional view through the vehicle showing one side of the cocktail lounge in elevation and taken on line 3—3 of Fig. 2;

Fig. 4 is also a vertical longitudinal sectional view through the vehicle showing the other side of the cocktail lounge in elevation and taken on the line 4—4 of Fig. 2;

Fig. 5 is a vertical transverse sectional view through the vehicle showing one end of the cocktail lounge in elevation, taken on the line 5—5 of Fig. 3;

Fig. 6 also is a vertical transverse sectional view through the vehicle showing the other end of the cocktail lounge in elevation and taken on the line 6—6 of Fig. 3;

Fig. 7 is a vertical longitudinal sectional view through the vehicle, taken on the line 7—7 of Fig. 2, showing the cocktail lounge in elevation from the passageway;

Fig. 8 is a vertical transverse sectional view through the vehicle, taken on the line 8—8 of Fig. 3, showing the central portion of the cocktail lounge;

Fig. 9 is a perspective view of one end of the cocktail lounge; and

Fig. 10 is a perspective view of the other end of the cocktail lounge.

The characteristic features of the present design reside in the interior cocktail lounge design shown in the drawings. The dominant features of my design reside in those portions shown in full lines.

What is claimed is:

The ornamental design for a railway car body, substantially as shown and described.

STANLEY W. KAY.
